UNITED STATES PATENT OFFICE.

IRVING F. WEBB, OF ELIZABETH, NEW JERSEY, ASSIGNOR TO THE SINGER MANUFACTURING COMPANY, A CORPORATION OF NEW JERSEY.

ADJUSTABLE CARRIER FOR SEWING MACHINES.

1,424,698.

Specification of Letters Patent. Patented Aug. 1, 1922.

Application filed March 10, 1919. Serial No. 281,812.

To all whom it may concern:

Be it known that I, IRVING F. WEBB, a citizen of the United States, residing at Elizabeth, in the county of Union and State of New Jersey, have invented certain new and useful Improvements in Adjustable Carriers for Sewing Machines, of which the following is a specification, reference being had therein to the accompanying drawings.

10 This invention relates to improvements in the mounting, control and convenient manipulation of sewing machines to better meet the requirements of seam-formation in materials presented to the stitch-forming mechanism by devices actuated and controlled independent of the operating mechanism of the sewing machine, as in machines for closing the mouths of filled sacks. The primary object of the present invention is to 20 adjustably secure the sewing machine against accidental adjustment when in its operative position, but unsecured against adjustment to an idle position out of its operative field. The invention further consists in the various 25 matters, all as hereinafter described and referred to in the appended claims.

Referring to the drawings, which form a part of the specification Fig. 1 is a view in perspective of a sewing machine secured on 30 a table top mounted on a suitable frame (the latter only partly illustrated) in stitch-forming position, together with the present improved means for effecting oppositely directed vertically arranged adjustments of 35 said machine. Fig. 2 is a view in perspective similar to Fig. 1 with the sewing machine adjusted to its idle position. Fig. 3 is a view, mainly in section, of the means employed for effecting adjustments of the sewing 40 machine when occupying its operative position. Fig. 4 is a view in perspective of a portion of the frame base illustrating the manually operated treadle for controlling the action and inaction of the stitch-forming 45 mechanism.

Referring to the drawings 1 represents a sewing machine of which the stitch-forming and cloth-feed actuating mechanism is substantially as disclosed in the patent to W. H. 50 Hugg, No. 1,005,840, October 17, 1911. No detailed disclosure of this mechanism is herein made, as the invention is applicable to any form of sewing mechanism including the work-holding devices between which the 55 work is held as it is fed past the point of

seam-formation. The sewing machine is suitably secured to a plate 2 carried by a hinged-bracket 3 pivoted at 4 to a hinge-bracket 5 suitably secured to a table top 6 of the frame 6', and on said hinged-bracket 60 is suitably secured an electric motor 7, operatively connected by a belt 8 with loose and tight pulleys 9 and 10 of the sewing machine, the arrangement of the motor and said pulleys with respect to the pivot 4 being such 65 that under all conditions of adjustment of said machine about the latter the same driving relationship is maintained.

11 represents a screw-threaded rod pivoted at 12 to a bracket 13 suitably secured to the 70 table top and 14 a nut threaded on said rod and provided with a cone-shaped surface 15. 16 denotes a tubular nut-actuating element suspended by screws, as 17, from the bevel gear 18 and provided with an inner cone-shaped surface 18' normally in engagement with the cone-shaped surface 15 of the nut 14. 19 denotes a collar surrounding the element 16 into which pintle screws 20 and 21 are seated after having been threaded into openings 22 and 23 respectively in the respective 75 brackets 24 and 25 formed integral with the hinged bracket 3, and between the collar 19 and the surface 26 of the element 16 bearing balls 27 are introduced to better provide for 80 the rotation of said element with respect to the stationary collar 19. 28 denotes a hand-wheel mounted to turn on the binder screw 21 and provided with a knob 29 and hub 30, the latter, through the screws as 31, 85 carrying the bevel gear 32 meshing with the gear 18 the rotation of which through the contacting cone-surfaces 15 and 18', causes the nut 14 to track the threaded rod 11, when for any purpose, it is desired to raise or 90 lower the sewing machine head within its field of stitch-formation.

From the foregoing it will be understood that the sewing head may be given oppositely directed vertically arranged adjustments on the threaded rod 11 by the manual manipulation of the hand-wheel 28 and that when it is desired to adjust said head to its position of rest out of its position of seam-formation, as illustrated in Fig. 2, for the 100 purpose of cleaning, oiling, adjusting etc., such adjustments are in no way controlled by said hand-wheel.

33 represents a belt-shifting lever pivoted at 34 to a bracket 35 suitably secured to the 110

plate 2 and provided with belt-shifting pins as 36, brake-element 37 and an adjustably secured belt shifting weight 38, the opposite end of said lever being provided with an extension 39 to which is suitably secured a flexible belt shifting connection 40 passing over an idler 41 provided with a guard 42, said connection passing through a suitable opening (not shown) in the table top and at 10 its lower end suitably attached to an arm 43 of a bell-crank-lever 44 whose second arm 45 is acted on by an oscillated treadle 46 pivoted on a stud 47 secured in the frame base 48, said treadle being limited in its 15 movements to shift the belt 8 by a stationary pin 49.

As will be readily understood the operator 20 operates the treadle in the direction indicated by the arrow S by moving the foot against the up-turned portion 50 in opposition to the gravity action of the weight 38 to shift the belt 8 from the loose to the tight pulley, the action of the weight returning said belt to its normal position when the foot is moved 25 out of engagement with the treadle.

While the present improved means is designed more particularly for use in connection with constructions of the character employed for closing the mouths of filled sacks, 30 such for instance, as is represented by U. S. Patent No. 1,274,742, August 6, 1918 to G. E. Molyneux, it is not deemed necessary to illustrate or describe such construction as it has no bearing on the present improved 35 means except to illustrate a single application of the present invention.

Having thus set forth the nature of the invention, what I claim herein is—

1. In a device of the character described, 40 the combination with a sewing machine, of a hinged-bracket supporting said sewing machine, an electric motor carried by said bracket, and connections between said motor and said machine for transmitting power to the latter.

2. In a device of the character described, 45 the combination with a sewing machine, of a hinged-bracket supporting said sewing machine, means for effecting adjustments of said machine about the axis of said hinged-bracket, an electric motor carried by said hinged-bracket, and connections between said motor and said machine for transmitting power to the latter.

3. In a device of the character described, 50 the combination with a sewing machine, of a hinged-bracket supporting said sewing machine, means for maintaining given adjustments of said bracket about its axis, an electric motor carried by said bracket, and connections between said motor and said machine for transmitting power to the latter.

4. In a device of the character described, 55 the combination with a sewing mechanism including work-holding devices for holding

the work therebetween, of adjusting means for altering the sewing position of said sewing mechanism, including coacting devices freely separable independently of said adjusting means to at will permit movement 70 of said sewing mechanism to inoperative position.

5. In a device of the character described, the combination with a sewing mechanism including work-holding devices for holding 75 the work therebetween, of coacting devices normally self-maintained in operative relationship whereby the sewing position of said sewing mechanism may be altered at will, but freely permitting separation without adjustment thereof to at will move said sewing mechanism to inoperative position.

6. In a device of the character described, the combination with a sewing mechanism including work-holding devices for holding 80 the work therebetween, and a hinged-bracket supporting said sewing mechanism, of coacting devices of which one is sustained by said hinged bracket and is normally maintained in operative relationship with its co- 85 acting device whereby the sewing position of said sewing mechanism may be altered at will, said coacting devices being freely separable independently of any adjustment thereof to at will permit movement of said 90 sewing mechanism to inoperative position.

7. In a device of the character described, the combination with a sewing mechanism, of a threaded rod, a pivotal support for said rod, a nut threaded on said rod, and a device coacting with said nut for altering the 100 sewing position of said sewing mechanism, but freely separable from said nut without adjustment to permit movement of said sewing mechanism to inoperative position. 105

8. In a device of the character described, the combination with a sewing machine, of a hinge-bracket to which the latter is secured means including a threaded rod provided with a nut, together with means carried by 110 said bracket for actuating said nut through frictional engagement with said latter means, said rod, nut and said means carried by said bracket cooperating to effect adjustments of and secure said machine against 115 accidental adjustment when in its position of seam-formation but separable to permit of its adjustment to an idle position out of its field of seam-formation independent of said rod, nut and said means carried by said 120 bracket-arm.

9. In a device of the character described, the combination with a sewing machine, of a hinged-bracket to which the latter is secured, means including a threaded rod tracked by a 125 nut having an external cone-shaped surface, together with an internal cone-shaped co-operating driving member for effecting adjustments of and to secure said machine against accidental adjustment when in its 130

position of seam-formation, but permitting of its adjustment to an idle position out of its field of seam-formation independent of the nut and said cooperating member.

- 5 10. In a device of the character described, the combination with a sewing machine, of a hinged-bracket to which the latter is secured, an electric motor carried by said bracket and connections between said motor
- 10 and said machine for transmitting power to the latter, a belt-shifting lever controlled, through a flexible connection and suitable treadle, to effect and to arrest said power transmission, said flexible connection track-
- 15 ing an idler the axis of which is located with respect to the axis of said bracket to maintain a like control of said lever under all conditions of adjustment of said machine within its field of seam-formation.
- 20 11. In a device of the character described, the combination with a sewing machine, of a hinged-bracket to which the latter is secured, an electric motor carried by said bracket and connections between said motor and said
- 25 machine for transmitting power to the latter, a belt shifting lever controlled, through a flexible connection and suitable treadle, to

effect and to arrest said power-transmission, said flexible connection tracking an idler the axis of which is located, with respect to the 30 axis of said bracket, to maintain a like control of said lever under all conditions of adjustment of said machine within its field of seam-formation, said idler being provided with a guard for retaining said connection 35 in engaging relationship with the idler when said machine is being adjusted in opposite directions outside its operative field.

12. In a device of the character described, the combination with a sewing machine, of a 40 hinged-bracket to which the latter is secured, said bracket having an opening into which is pivotally mounted a collar, a tubular nut-actuating element surrounded by said collar, a threaded rod and a nut adapted to track 45 the threaded rod and frictionally engaged by said element, said collar acting on said actuating element to, through suitable power transmitting elements, cause said nut to track said rod.

In testimony whereof, I have signed my name to this specification.

IRVING F. WEBB.
